Primary Examiner — John Windmuller(74) *Attorney, Agent, or Firm* — Patterson Thuente Christensen Pedersen, P.A.(57) **CLAIM**

I claim the ornamental design for an antenna, as shown.

DESCRIPTION

FIG. 1 is a front perspective view of an antenna depicting a representative embodiment of my new design;

FIG. 2 is a front elevation view of the antenna of FIG. 1;

FIG. 3 is a right-side elevation view of the antenna of FIG. 1;

FIG. 4 is a top plan view of the antenna of FIG. 1;

FIG. 5 is a rear elevation view of the antenna of FIG. 1;

FIG. 6 is a bottom plan view of the antenna of FIG. 1; and,

FIG. 7 is a left-side elevation view of the antenna of FIG. 1. The broken lines and the areas within broken lines in the figures depict portions of the antenna that form no part of the claimed design.
